[57] CLAIM

The ornamental design for a two-way mobile radio, as shown and described.

DESCRIPTION

FIG. 1 is a top, front and left side perspective view of a two-way mobile radio showing my new design; FIG. 2 is a left side elevational view thereof; FIG. 3 is a right side elevational view thereof; FIG. 4 is a front elevational view thereof; FIG. 5 is a rear elevational view thereof; FIG. 6 is a top plan view thereof; FIG. 7 is a bottom plan view thereof; and FIG. 8 is a front elevational view of a second embodiment of the control head illustrated in FIG. 1; The left side, right side, rear, top and bottom views of the embodiment disclosed in FIG. 8 are identical to the corresponding views of the embodiment disclosed in FIG. 1.

FIG. 1

FIG. 2

FIG. 3

FIG. 4

FIG. 5

FIG. 6

FIG. 7

FIG. 8
